UNITED STATES PATENT OFFICE.

ANTON SCHMIDT, OF VIENNA, AUSTRIA-HUNGARY, ASSIGNOR TO MARIE HOLUBEK, OF SAME PLACE.

STREET-CLEANING MACHINE.

SPECIFICATION forming part of Letters Patent No. 684,618, dated October 15, 1901.

Application filed May 14, 1901. Serial No. 60,142. (No model.)

To all whom it may concern:

Be it known that I, ANTON SCHMIDT, painter, a subject of the Emperor of Austria-Hungary, residing in XVII, Beheimgasse 38, Vienna, 5 Austria-Hungary, have invented certain new and useful Improvements in Street-Cleaning Machines; and I do hereby declare the following to be a full, clear, and exact description of the invention, such as will enable others 10 skilled in the art to which it appertains to make and use the same, reference being had to the accompanying drawings, and to numerals of reference marked thereon, which form a part of this specification.

15 The present invention has reference to improvements in street-cleaning machines, and relates more especially to a street-cleaning machine of the wagon type provided with running-gear and adapted to be propelled 20 by animal or machine power. The wagon-body in the present invention is divided into three distinct parts or compartments, the front compartment constituting the receptacle for the dirt or snow taken up from the 25 street, the middle compartment containing two endless conveyers arranged parallel, or approximately so, to one another, the one scraping or brushing up the dirt or snow from the street and carrying it to the other one, 30 which in its part carries it to the aforementioned receptacle, and the third compartment containing water for sprinkling purposes.

In order to make the invention more readily understood, I have illustrated it on the accompanying sheets of drawings, in which—

35 Figure 1 represents a vertical sectional elevation of a street-cleaning machine according to my invention. Fig. 2 represents a fragment of a somewhat-modified form of construction, scoops being here employed in lieu of the brushes shown in Fig. 1. Fig. 3 is a perspective view of a rolling dust-guard for confining the dust at the point of contact of the main conveyer with the ground. Fig. 4 45 illustrates my improved form of mounting for the elevating devices of the conveyers; and Fig. 5 represents a form of brush conveyer, partly in section, for car-rail-cleaning purposes.

50 Referring to the drawings, 2 is the wagon-body, carried by wheels 1, which is divided

into three compartments 16, 37, and 28, respectively. In the middle compartment 37, Fig. 1, is arranged obliquely a brush conveyer, consisting of an endless belt, band, or 55 chain 5 running over suitably-journaled revolving disks 3 and 4. To the part 5 I shall hereinafter refer as a "band;" but I want it to be particularly understood that it may be any other form of substantially similar flexible 60 device. Upon this band 5 are secured brushes consisting of cross-bars 7 and brush-tufts 6, mounted in said cross-bars. The travel of the band 5 is attained by teeth 8, fastened to the inside of the band, engaging correspond- 65 ing recesses 9, provided in the circumference of the disks 3 4 in the usual manner. The other conveyer is of the cup type and is arranged parallel or approximately parallel to the brush conveyer. This cup conveyer consists of an endless band 12 running over recessed revolving disks 10 11, suitably journaled, and of cups 13, made up of two side flaps and the preferably slightly-curved front, as is clearly shown in Fig. 4. The power for 70 setting in motion the two conveyers is derived from a sprocket-wheel 22, secured upon one of the wagon-wheel axles. A link chain 21 transmits the power to a sprocket-wheel 23, secured upon the axle 24 of the recessed 80 disk 11. Upon this axle 24 is likewise secured a cog-wheel 25, meshing with the cog-wheel 26, fast upon the axle 27 of the recessed disk 3. When the machine is moved forward, the conveyers are caused to travel in the 85 direction of the arrow, Fig. 1.

The operation of the machine is as follows: The brush conveyer carries the dirt against and up the inclined shield 15 and throws it into the cups 13 of the other conveyer, which 90 travels with the same speed. As the brush-tufts of the one conveyer more or less enter the spaces between the cups of the other conveyer similar to the intermeshing of toothed rods or racks, the dirt is effectually prevented 95 from falling back again and is carried upward and finally deposited into the compartment 16.

In order to prevent the dirt from sticking and clogging up the cups, these latter preferably are journaled loosely with their trunnions 14 in eye-bearings 19, secured to the

conveyer-band 12, as shown in Fig. 4. A spring 20 ordinarily retains the cup in the position shown in Fig. 4. When each cup reaches its highest position—*i. e.*, the position 5 where the dirt is to be dumped out into the receptacle 16—a catch 17 retains for a short period the outer end of the cup and causes it to tilt backwardly, the conveyer meanwhile traveling on. Upon the cup being drawn 10 from underneath the catch 17 it is violently jerked forward by the spring 20, whereby any sticking dirt or mud is caused to part from the cup.

Instead of arranging the cups in the just- 15 described manner the endless band 12 may be made elastic, so that upon the respective cup being retained by the catch 17 the band 12 is stretched and by its tension causes a sudden shaking of the cup, when the latter 20 comes free from the catch.

For allaying the dust stirred up by the operation of the machine water may be sprinkled out of the finely-perforated tube 30, which receives the water from the tank 28 by 25 aid of the cock or valve 29.

Where dust in large quantities or snow is to be dealt with, the brush conveyer is preferably replaced by a scoop conveyer, as shown in Fig. 2. The scoops 31 are fastened to the 30 endless band 5 by means of elastic hinges 32 in the manner described above with reference to the cups 13. This arrangement serves a double purpose. In the first place the scoops are protected against damage when 35 striking irregularities of the pavement, and, secondly, they are also acted upon by the stationary catch 17' for loosening up the contents.

In connection with the last-described scoop- 40 conveyer arrangement there may be provided back of the scoop conveyer a three-sided frame 33, (shown separately in Fig. 3,) running upon small wheels 34 and attached to the walls of the machine by means of screw- 45 bolts 36 gliding in longitudinal slots 35, so that the frame which serves to hold down the dust can rise and fall with the irregularities of the ground. This dust-frame is easily attached to or removed from the ma- 50 chine and can of course also be made use of

in connection with the first-described brush conveyer.

In Fig. 5 is shown a form of construction of the brush conveyer adapted for cleaning car-rails. The band 5, carrying the cross-bars 7 with brush-tufts 6, is approximately of the width of the rail and runs over recessed disks 4.

What I claim, and desire to secure by Letters Patent, is—

1. In a street-cleaning machine, the combination of the body, endless flexible conveyers arranged substantially parallel and in operative contiguity to each other, one of said conveyers being adapted to take refuse from the ground and the other being adapted to take the refuse from said first-named conveyer, a compartment in said body, said other conveyer being adapted to discharge into said compartment, mounting means for said conveyers, means for advancing said conveyers in relatively opposite directions, one of said conveyers comprising elastically controlled and yielding elevating devices, and a catch arranged in said body in the path of movement of said devices, substantially as described. 65

2. In a street-cleaning machine, the combination of the body, an endless flexible band arranged in said body, a refuse-receiving compartment in said body, mounting means for said band, means for advancing said band, bearings on said band, scoops having trunnions journaled in said bearings, springs controlling said scoops, and a catch arranged in said body in the path of movement of said 75 scoops, substantially as described.

3. In a street-cleaning machine, the combination of a three-sided dust-frame, wheels supporting the said frame, and screw-bolts secured to either side of the said frame and 80 adapted to glide within longitudinal slots provided in the machine side parts, substantially as and for the purpose set forth.

In testimony that I claim the foregoing I have hereunto set my hand this 24th day of April, 1901.

ANTON SCHMIDT.
